UNITED STATES PATENT OFFICE

162,896

PIN OR SIMILAR ARTICLE

Joseph Sternberg, New York, N. Y., assignor to Paul Flato Sales Corporation, New York, N. Y.

Application January 12, 1951, Serial No. 13,782

Term of patent 7 years

(Cl. D45—19)

To all whom it may concern:

Be it known that I, Joseph Sternberg, a citizen of the United States of America, residing in New York city, county of New York, and State of New York, have invented a new, original, and ornamental Design for a Pin or Similar Article, of which the following is a specification, reference being had to the accompanying drawing, forming part thereof, wherein:

The jewels are lined to indicate color contrast.

I claim:

The ornamental design for a pin or similar article, substantially as shown and described.

JOSEPH STERNBERG.
